US00D997267S

(12) **United States Design Patent** (10) **Patent No.:** **US D997,267 S**
(45) **Date of Patent:** **** Aug. 29, 2023**

- (54) **WALL MOUNTED EXERCISE RACK**
(71) Applicant: **Coulter Ventures, LLC.**, Columbus, OH (US)
(72) Inventors: **Nash Dunahay**, Blacklick, OH (US); **Martin Pritchett**, Hilliard, OH (US)
(73) Assignee: **Coulter Ventures, LLC.**, Columbus, OH (US)
(**) Term: **15 Years**
(21) Appl. No.: **29/805,005**
(22) Filed: **Aug. 24, 2021**

Related U.S. Application Data

- (63) Continuation of application No. 29/763,613, filed on Dec. 23, 2020.

CLAIM

The ornamental design for a wall mounted exercise rack, as shown and described.

DESCRIPTION

FIG. 1 is a top, front, right perspective view of the wall mounted exercise rack showing our new design;

FIG. 2 is a front view thereof;

FIG. 3 is a left side view thereof; and,

FIG. 4 is a top view thereof.

The broken lines in the drawings illustrate portions of the wall mounted exercise rack that form no part of the claimed design.
